ATTORNEY

UNITED STATES PATENT OFFICE

ROBERT L. DAVIS, OF PITTSBURGH, PENNSYLVANIA, ASSIGNOR TO WESTINGHOUSE ELECTRIC & MANUFACTURING COMPANY, A CORPORATION OF PENNSYLVANIA

TELEVISION

Application filed June 23, 1928. Serial No. 287,823.

My invention relates to television systems, and more especially to systems of the type wherein the view to be transmitted is analyzed at the sending station by a mechanically actuated scanning device, and at the receiving station, is reproduced through the agency of a similar device which is actuated in synchronism with the device at the sending station.

10 Although the broad principle underlying my invention is applicable to a wide variety of television systems, it is particularly useful in connection with systems wherein the scanning devices take the form of revolute disks, each disk being provided with a spirally disposed series of axial openings extending therethrough.

At the sending station, a scanning disk of the type described is interposed between a 20 source of light and the object, a view of which is to be transmitted and, by being revolved at a high rate of speed, causes a spot of intense light to traverse every portion of the object. The light reflected from the object 25 falls on a photo-electric cell, or a plurality of cells, thus controlling a current which is either transmitted direct to the receiving station or is utilized to modulate the output of a radio-transmitter. The British patent to 30 Baird, 269,658, exemplifies a television transmitter of the type referred to.

At the receiving end, a voltage-responsive light source is provided, and the supply circuit therefor is so arranged that the brilliancy of the light is proportional to the modulated energy coming from the sending station. A scanning disk, similar to the disk at the sending station, is interposed between the light-source and a viewing lens and, when 35 it is revolved in step with the transmitting disk, causes the eye of the observer to receive substantially the same visual impression as would be received from the actual object.

40 In order that a correct visual impression shall be received by the observer, it is essential that the two disks shall revolve at the same angular velocity and that they shall be in exact step. If the receiving disk differs 45 in angular relation to the sending disk the

received picture will not be "framed" properly, but will be seen as either too high or too low in the viewing lens, depending on the direction of rotation of the disk with respect to the spiral series of openings.

It has previously been proposed to "frame" the received picture by permitting the motor driving the receiving disk to drop momentarily out of synchronism and "slip poles" until the picture appears to be about right, and a differential arrangement for accomplishing the same result is disclosed in the patent to Ramsey, 1,602,121. Neither method has given entire satisfaction, however, since both of them involve what might be described as "trial-and-error" adjustment.

It is, accordingly, an object of my invention to provide means for "framing" the received picture in a television system that shall be positive in action and simple to manipulate.

Another object of my invention is to provide means for "framing" the received picture in a television system that shall be independent of the speed of revolution of the scanning device.

Another object of my invention is to provide, in a television system, means for "framing" the received picture that shall not require "trial-and-error" adjustment.

In the specific modification of my invention that has been chosen as illustrative of the principle thereof, the scanning device at the receiving station takes the form of a revolute disk provided with a series of openings arranged along a spiral of two revolutions, such as is illustrated in the aforementioned Ramsey patent. The variable light source, the viewing-frame, and the viewing lens, which elements are hereinafter designated the "viewing-assembly", however, are not fixed in position relative to the scanning disk, but are mounted for adjustment radially thereof by means of a rack and pinion. The observer, therefore, by adjusting the position of the viewing-assembly with respect to the radius of the scanning disk, may utilize any portion of the double spiral of holes for scanning purposes, and may thus "frame" the received view in a simple and positive manner.

during the operation of the system without altering the angular velocity of the receiving disk.

The novel features that I consider characteristic of my invention are set forth with particularity in the appended claims. The invention itself, however, both as to its organization and its method of operation, together with further objects and advantages thereof, will best be understood by reference to the following description of a specific embodiment, taken with the accompanying drawing, in which:

Figure 1 is a view, in elevation, of a television receiver comprising a preferred embodiment of my invention, and

Fig. 2 is a sectional view, taken along a line corresponding to the line II-II of Fig. 1.

The apparatus illustrated in the drawings comprises a disk 1 provided with a large number of scanning-openings 2 disposed in a spiral having a plurality of convolutions. The disk is preferably designed to rotate in a vertical plane, being either mounted directly on the shaft of a constant-speed motor or geared thereto.

A viewing-assembly, comprising a variable light source 4, preferably a glow-lamp, a viewing or framing aperture 5, and an enlarging lens 6, is so disposed with respect to the disk that light from the glow-lamp is visible to an observer through only one of the scanning openings 2 at a time.

The glow-lamp, is a preferred modification of my invention, comprises a plurality of flat electrodes 20 and 21, which are mounted in a bulb 22 containing neon gas under very reduced pressure. The electrodes are spaced apart a distance less than the mean free path of the gas molecules and, consequently, the discharge between them necessarily spreads out around the edges and takes place between the surfaces which are not closely adjacent. The specific type of glow lamp employed forms no part of my invention, it being perfectly feasible to replace it by any other light source, the luminosity of which may be caused to vary in response to incoming voltage variations.

The viewing-assembly is mounted on a vertically-movable frame 7 which is provided with a rack 8 arranged to mesh with a pinion 10. The pinion 10 is provided with control knob 11 located where it may conveniently be manipulated by an observer.

The size of the viewing aperture 5 is so chosen that its vertical dimension is slightly less than the radial distance between successive convolutions of the scanning-opening spiral, and it is disposed at such distance from the disk that only one opening is instantaneously visible therethrough.

In the operation of my improved television receiver, the disk is first caused to rotate at a high rate of speed, in synchronism with a

similar disk at a transmitting station. The lamp is then supplied with sufficient potential to cause it to glow, and the received impulses representative of light variations in the view being transmitted, are impressed across the terminals thereof.

As soon as the receiving disk has been brought into synchronism with the transmitting disk, which may be accomplished by any method well known to those skilled in the art, the observer, by looking through the viewing lens toward the disk, sees a reproduction of the view being transmitted. If the instantaneous angular position of the receiving disk differs from that of the transmitting disk, however, the picture seen by the observer will not be properly "framed," but will appear too high or too low in the viewing aperture. The reason for this displacement lies in the fact that the openings in the receiving disk are either instantaneously higher or instantaneously lower with respect to the aperture 5 than are the openings in the transmitting disk with respect to its aperture.

If the picture appears to be too high in the viewing aperture, the viewing-assembly is moved upward. If the picture appears to be too low, the viewing assembly is moved downward. The movements may, however, be in the opposite directions if the viewing-assembly is at the limit of its travel just preceding the adjustment. The movement of the assembly either upward or downward is equivalent to giving the disk an angular movement backward or forward with respect to the direction of rotation, independently of the motor drive and, since the scanning-openings are arranged in a spiral having two or more revolutions, the equivalent angular advance or retardation of the disk may be made any amount from a few seconds of arc up to and past 360°.

If the light source is sufficiently large, it is not necessary to raise or lower it simultaneously with the viewing lens and viewing aperture, but it may remain fixed in position during the framing operation. It might also, in some cases, be simpler to fix the entire viewing-assembly, and to raise or lower the motor and disk, the same relative amount.

I have, accordingly, provided a television receiver in which the picture may be simply and expeditiously framed without the necessity of a plurality of "trial and error" adjustments. After the framing has once been accomplished, it remains substantially perfect unless the driving motors for the disks at the transmitting and the receiving stations depart from synchronism.

Although I have chosen to illustrate my invention as applied to a television system of the type wherein scanning-disks are used, it is not to be restricted to the specific apparatus illustrated. Many modifications of

my invention will be apparent to those skilled in the art and it is my intention that its scope shall be limited only insofar as is necessitated by the prior art or by the spirit of the appended claims.

5 I claim as my invention:

1. In a television receiver, a scanning device, motive means for said device, a viewing-assembly, and means for moving said viewing-assembly bodily in a radial direction

10 with respect to said scanning means, whereby the effect of a change in the angular relation between said scanning device and said motive means is obtained and the received picture may be framed.

15 2. In a television receiver, a rotatable disk provided with scanning openings disposed in a spiral having a plurality of convolutions, a viewing-assembly, and means for moving said viewing-assembly radially of said disk.

20 3. In a television receiver, a rotatable disk provided with scanning openings disposed in a spiral having a plurality of convolutions, a viewing-assembly comprising a variable light source, a viewing aperture and a viewing lens, and means for moving said viewing-assembly radially of said disk.

25 4. In a television receiver, a rotatable disk provided with scanning openings disposed in a spiral having a plurality of convolutions, a variable light source, a viewing aperture and a viewing lens, and means for moving said viewing-assembly radially of said disk.

30 5. In a television receiver, a rotatable disk provided with scanning openings disposed in a spiral having a plurality of convolutions, a variable light source disposed adjacent to said openings at one side of said disk, means disposed adjacent to the other side of said disk for observing the illuminated openings, and means for moving said viewing means radially of said disk.

35 6. In a television receiver, a rotatable disk provided with scanning openings disposed in a spiral having a plurality of convolutions, a variable light source disposed adjacent to said openings at one side of said disk, viewing means comprising a frame and a lens disposed adjacent to the other side of said disk for observing the illuminated openings, and means whereby said viewing means may be moved radially of said disk.

40 In testimony whereof, I have hereunto sub-
55 scribed my name this 18th day of June, 1928.

ROBERT L. DAVIS.
